UNITED STATES PATENT OFFICE

CLIFFORD L. SNYDER, OF DETROIT, MICHIGAN, ASSIGNOR TO THE EVANS AUTO
LOADING CO. INC., OF DETROIT, MICHIGAN

METHOD OF MAKING REINFORCING CORNER STRAPS FOR EXPORT BOXES
AND THE LIKE

Application filed January 23, 1930. Serial No. 422,826.

This invention relates to certain new and useful improvements in reenforcing corner straps for export boxes and the like.

The primary object of this invention is to provide a reinforcement for the corners of shipping boxes and the like in the form of a metallic strap of triangular form to be mounted upon and have the sides thereof traverse three sides of the box and to be struck or drawn from a single blank of material for bracing the box corner against movement in all directions and especially to restrain from movement, the strips, boards or stringers comprising the box wall.

A further object of the invention is to provide a reenforcing corner strap for export boxes and the like wherein the corner strap is drawn from a triangular blank having outwardly curved sides and curved fillets at the inner angles of the blank so that when drawn by a punch or the like to present the side strips or sections of the strap for flat contact with the box side, the opposite edges of the initially curved sections of the strap are moved into parallelism while the corner bends are maintained against disruption by the curved fillets, the corner strap being contiguous throughout the length thereof, formed of a single piece of material and free of folds, bends or connections in any part and especially in the side sections thereof.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a fragmentary perspective view of an export box or the like with the reenforcing corner straps engaged with the corner of the box;

Figure 2 is a fragmentary side elevational view;

Figure 3 is a detail sectional view taken on line 3—3 of Figure 1;

Figure 4 is a plan view of the blank from which the corner strap is drawn showing the

initially curved inner and outer sides of the side sections of the corner strap and the curved fillets at the inner angles of the corner bends;

Figure 5 shows side elevational views of a punch, strap blank and drawn strap; and

Figure 6 is an outer side view of the corner strap.

The device disclosed in this application is for the reinforcement of corners of export boxes and the like and is in the form of a triangular strap to be engaged with three sides of a box at the corner to be anchored to the box strips and stringers for holding them against movement relative to each other and to maintain the box in true shape and form. Numerous attempts have heretofore been made to reinforce the corners of boxes by strap irons and the like, such attempts including corner straps formed of several sections as well as single sections embodying overlapped folded parts as well as connected ends, but in all such instances, these straps have utterly failed in performing their functions as the connections between the strap sections become loosened permitting expansion and failing as a reinforcement. In the present application, the corner strap is drawn from a triangular blank formed of a single piece of material and when pressed or drawn into the proper shape is free of any folds or joints so that expansion of any part thereof is impossible and when anchored to the corner of a box or the like, the strips, boards and stringers comprising the box are maintained against relative movement to resist strains in any direction.

The reenforcing corner strap is formed from a triangular blank, preferably by a drawing operation, the blank as shown in Figure 4 comprising three side sections 10 having their inner and outer edges curved outwardly as at 11 and 12 respectively with a curved fillet 13 at each angle corner of the blank. A nail receiving opening 14 is provided in each side section 10 adjacent each end to facilitate anchoring of the strap to the corner of the box in a manner later to be described.

With the use of the triangular punch 15

shown in Fig. 5, the strap blank which normally has its side sections 10 lying in a single plane as at 10a, the side sections 10 are moved into the form shown in Figs. 5 and 6 by a drawing operation, during which the inner and outer curved edges 11 and 12 respectively of the side sections 10 are moved into straight lines as shown at 11a and 12a while the curved fillets 13 prevent tearing of the blank or other disruption at the angle corner, it being noted from an inspection of Figure 5, that the lower corners 15a of the punch 15 are slightly rounded to prevent disruption. The side sections 10 are moved at right angles to each other in the formation of the triangular corner bracing strap for flat contact with side faces of an export box or the like comprising side boards 16 and internal stringers. The corner strap is anchored in position by nails 17 or the like driven through the openings 14 in the side sections 10 to enter the boards 16 and stringers of the box as shown in Fig. 3. With this form of corner strap, the box stringers 16 are restrained against movement in all directions and by the single piece construction of the corner strap, being continuous and free of folds, bends or joints, expansion of the strap is impossible resulting in a rigid anchor for the box stringers at the corners of the box. With the particular design of blank employed in the drawing operation resulting in the corner straps, the latter embodies increased strength from the initially curved inner and outer sides 11 and 12 respectively of the side sections 10; while any tendency of disruption at the point 13 of the angles is eliminated by the presence of curvature therein.

From the above detailed description of the invention, it is believed that the method of construction and use of the same will at once be apparent and while there is herein shown and described the preferred embodiment of the invention, it is nevertheless to be understood that minor changes may be made therein without departing from the spirit and scope of the invention as claimed.

I claim:

1. The method of forming a reenforcing corner strip for boxes and the like consisting of cutting a blank of triangular formation wherein the sides of the triangle consist of parallel curved strips, then drawing this shape from a single plane into the form of a triangular pyramid whose sides are at right angles to each other, and at the same time straightening the curved parallel sides of the triangle to a straight parallelism.

2. The method of forming a reenforcing corner strap for shipping boxes containing internal stringers, wherein the corner strap is anchored to the outer boards and internal stringers and wherein the strap is formed of a blank of substantially triangular form having its side sections outwardly arched de-

fining inner and outer concentric curved edges, said method consisting of cutting a blank of triangular formation with sides comprising curved strips, then drawing this shape from a single plane into bracing form with the faces of the side sections in planes at right angles to each other and simultaneously straightening the curved side sections to a straight parallelism.

In testimony whereof I affix my signature.

CLIFFORD L. SNYDER.
